UNITED STATES PATENT OFFICE.

DUNCAN MCLENNAN, OF CROYDON, ENGLAND.

MEANS FOR DETECTING SOUNDS.

1,297,206.

Specification of Letters Patent. Patented Mar. 11, 1919.

Application filed October 13, 1917. Serial No. 196,548.

To all whom it may concern:

Be it known that I, DUNCAN MCLENNAN, a subject of the King of Great Britain and Ireland, residing at Croydon, in the county 5 of Surrey, England, have invented Improvements in Means for Detecting Sounds, of which the following is a specification.

This invention relates to compound diaphragms for use in or with sound-transmitting and sound-receiving instruments or apparatus such as telephones, phonographs, stethoscopes, signaling instruments and the like.

A compound diaphragm arrangement according to the present invention comprises coaxial diaphragms mounted parallel to one another so as to form between them a closed space that is charged with liquid, the diaphragms being of different effective diameters and maintained apart at their peripheries by interposed peripheral distance pieces so as to insure their being kept parallel one to another, the central portion of the closed space between them being always free except for the contained liquid. More than two diaphragms may be thus arranged to form two or more spaces that are filled with liquid. With such an arrangement, the vibrations are rendered "dead-beat" by the liquid. Furthermore, when the two or several diaphragms are of different sections or thicknesses, and therefore of different periodicity values, the range of notes to which the combination will respond is considerably augmented.

Such a compound diaphragm arrangement with parallel diaphragms and interposed liquid, may be employed generally in or with sound-transmitting and sound-receiving instruments or apparatus.

The distance or distances between the elementary diaphragms should be small compared with the diameters of the diaphragms or at least compared with the diameter of the larger or largest diaphragm if the diaphragms differ greatly in diameter.

When this compound or combination diaphragm arrangement is applied say to a telephone transmitter, the microphone would be attached to one side and the air vibrations or waves caused by the voice would act on the other side.

Similarly, in the case of say a telephone receiver, the magnet poles would be applied to one side of the combination diaphragm and the listener's ear placed near the other.

Any suitable liquid may be used between the diaphragms. A liquid suitable for the purpose is a mixture of distilled water and glycerin.

In the accompanying drawings, Figure 1 is a face view and Fig. 2 a section on the line 2-2 of Fig. 1 showing one example of a compound diaphragm arrangement having elementary diaphragms of different effective diameters with liquid chamber according to the invention. Figs. 3 and 4, are similar views of another example of a compound diaphragm according to the invention.

The compound diaphragm arrangement shown in Figs. 1 and 2 comprises two circular metal diaphragms *a* and *b* secured to the opposite sides of a ring *c* recessed so that the effective portions of the two diaphragms secured to its opposite sides are in effect of different diameters for the purpose hereinbefore explained. The ring may be of any suitable material, metallic or non-metallic, for example vulcanite, so as to form therewith a closed chamber that is charged with liquid *d*. For the latter purpose the ring *c* may also be formed with two oppositely arranged holes *e* and *f* for exit of air and inlet of the liquid, these holes being afterward hermetically closed, as for instance by screws *g*, or caps. In this example the two diaphragms *a* and *b* are shown as of unequal thickness.

The closed chamber may be completely filled with liquid or only partly filled. When the ring *c* is of metal the diaphragms *a* and *b* may be secured thereto in a fluid tight manner as by soldering the parts together, or in any case the diaphragms and interposed ring, whether of metal or other material, may be clamped together between outer rings *c*¹, *c*², as by screws passing through the assembled parts.

In the compound diaphragm arrangement shown in Figs. 3 and 4 there are three diaphragms *a*, *b* and *h* clamped in place within a holder *i* by rings *j*, *k* and *m* respectively which may be screwed into the holder *i*, as shown, or be otherwise held together so as to form two interposed chambers charged with liquid *d*.

As will be readily understood, compound diaphragm arrangements such as described can be used in connection with apparatus of various kinds, some of which have hereinbefore been indicated, designed for the transmission, reproduction or detection of sounds,

electrically or otherwise. One application of such a compound diaphragm arrangement is described in the specification of another application for Letters Patent filed (13th 5 October 1917) by me Serial No. 196547, for use in connection with sound detecting apparatus. Other uses will be readily understood without further explanation.

What I claim is:—

- 10 1. A sound transmitting or receiving compound diaphragm comprising diaphragms arranged parallel to each other, means for connecting the peripheral portions of said diaphragms and liquid inclosed within the 15 space formed by said diaphragms the portion of the diaphragms exposed to the liquid being of different effective area.
- 20 2. A sound transmitting or receiving compound diaphragm comprising elementary diaphragms, means of different effective widths extending inwardly from the common peripheries of and in surface contact with said elementary diaphragms, said means correspondingly imparting different 25 effective diameters to the several said diaphragms and forming a liquid containing

chamber between opposed faces of the same and liquid inclosed within the space between said diaphragm substantially as described.

3. A sound transmitting or receiving compound diaphragm as claimed in claim 1, wherein the elementary diaphragms are of unequal thickness substantially as described.

4. A compound diaphragm arrangement as claimed in claim 1 comprising several co- 35 axial diaphragms with interposed rings between their peripheral portions and liquid between the adjacent pairs of diaphragms substantially as described.

5. A sound transmitting or receiving compound diaphragm as claimed in claim 1 carried by a circular holder substantially as described.

6. A sound transmitting or receiving compound diaphragm as claimed in claim 1 having oppositely arranged charging holes and sealing means for same, substantially as described.

Signed at London, England, this 20th day of September, 1917.

DUNCAN MCLENNAN.
